UNITED STATES PATENT OFFICE.

ORVILLE A. THRASHER, OF AMERICAN FORK, UTAH.

DRINKING FOUNTAIN OR TROUGH.

Application filed March 15, 1922. Serial No. 543,934.

To all whom it may concern:

Be it known that I, ORVILLE A. THRASHER, a citizen of the United States, residing at American Fork, in the county of Utah and 5 State of Utah, have invented a new and useful Drinking Fountain or Trough, of which the following is a specification.

This invention relates to a drinking fountain or trough and constitutes a continuation in part of my application filed August 10, 1921, Serial No. 490,642.

The device is intended to be used for supplying water to young chicks, one of the objects of the invention being to provide a 15 trough having means for keeping chicks out of it without, however, preventing them from having easy access to the water.

Another object is to provide improved means for holding the trough assembled 20 with a supply tank so that the parts will be held in proper relation to each other.

A further object is to provide a supply tank of novel construction having valved means for preventing the escape of water 25 therefrom when the tank is lifted from position on the trough, said means being opened automatically, however, when the tank is assembled with the trough so as to open communication between the tank and trough.

30 With the foregoing and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

40 In the accompanying drawings the preferred form of the invention has been shown.

In said drawings.

Figure 1 is a front elevation of the complete device.

45 Figure 2 is an enlarged section on line 2—2, Figure 1.

Figure 3 is a section on line 3—3, Figure 1.

Figure 4 is a bottom plan view of the tank.

50 Figure 5 is a section, on a reduced scale, taken on line 5—5, Figure 2, the trough being eliminated.

Figure 6 is an enlarged section through a portion of the trough and tank and show-

ing the valve unseated when the parts are 55 assembled.

Referring to the figures by characters of reference 1 designates a tank or container preferably formed with a frusto-conical top 2 having a central opening 3 in which is supported a ring 4 extending downwardly into the tank. A closure 5 having a depending circular flange 6 is adapted to be inserted into the ring 4 and has an annular flange 7 for bearing on a sealing gasket 8. 60 This closure is provided with upwardly diverging spring arms 9 having downturned rounded terminals 10. A supporting strip 11 extends upwardly from the tank 1 and has a clamping strip 12 hingedly connected thereto 65 as shown at 13. A link 14 is pivotally connected to the tank 1 at a point diametrically opposite the strip 11 and is adapted to swing to position around the free end of the clamping strip 12. To the upper or outer end of this link is pivotally connected a cam lever 15 adapted, when in holding position, to lie flat upon the strip 12 with its point of connection with the link 14 located 70 above a point between the ends of that portion of the lever bearing on the strip 12. Thus the cam lever is locked or fastened in holding position and cannot be moved to or from said position without placing the strip 12 and the arms 9 under abnormal 75 tension.

The bottom of the tank 1 has been indicated at 16 and is located above the lower edge of the wall of the tank so as to provide a compartment 17 beneath the water holding compartment 18 formed above the bottom 16. A portion of the wall of the compartment 17 is cut away as shown at 19 and extending outwardly from this wall at the side edges of the cut away portion or opening 19 are wings 20 which are parallel as shown.

An outlet tube 21 is extended downwardly from the bottom 16 at a point adjacent the opening 19 and mounted on the bottom 16 80 and concentric with the upper end of the tube 21 is a foraminous cage 22 in which is loosely mounted a valve such as the ball valve 23. This valve is designed to close the upper end of the tube 21 when the tank 100 is not assembled with the balance of the apparatus hereinafter described, thus preventing leakage while the tank is being carried.

A stop strip 24 is extended across the compartment 17 and preferably at right angles to the wings 20. It is to be understood that the tank herein described can be carried readily by means of the clamping strip 12. When it is desired to open the tank for filling or cleaning it the free end of the lever 15 is swung upwardly relative to the strip 12 and the link 14 is swung laterally to release said strip. The closure 5 can then be removed. To secure the closure in place it is merely necessary to reverse the foregoing operation, the strip 12 and lever 15 cooperating to hold the spring arms 9 under compression.

The trough portion of the device includes an elongated strip 25 constituting the base thereof and supported on this base is an elongated trough or gutter 26 having down-turned side portions or aprons, 27 which are secured to the sides of the base 25. One end of the base 25 and the trough 26 is adapted to extend into the compartment 17 and to abut against the stop strip 24, the sides or aprons 27 being snugly engaged by the wings 20 which thus serve to hold the trough properly assembled with the tank. A pin 28 is extended upwardly from the trough so that when the tank and trough are assembled by lowering the tank onto the trough, this pin will project through the tube 21 and lift the valve 23 from its seat so as to open communication between the tank and the trough. As soon as the tank is lifted from the trough, however, the valve 23 will be reseated to prevent leakage.

Secured to the aprons 27 by bolts 29 or the like are side strips 30, the said bolts being extended across the trough and adapted to rest upon the sides thereof as shown in Figures 1 and 2. The strips 30 are integral with inverted V-shaped portions 31 extending over the trough and also extending over and being secured to a longitudinally extended cover 32 of the same shape as the portions 31. This cover has a central ridge and depending from the ridge is a longitudinal partition 33. This partition has its lower edge supported near the center of the top of the trough and formed with notches 34.

By providing the partition the top portion of the trough is divided into parallel longitudinal spaces too small to allow chicks

to fall into the trough. The notches allow free circulation from one side of the trough to the other.

Obviously the device can be made of any size desired suitable for watering larger chickens or other live stock. Importance is attached to the fact that the parts can be readily disconnected for the purpose of cleaning them.

What is claimed is:

1. A device of the class described including a tank having upper and lower compartments, a closure for the upper compartment, a valve controlled outlet in the bottom of the upper compartment, a stop within the lower compartment, spaced wings outstanding from the wall of the lower compartment, and a trough insertable at one end between the wings and against the stop and into position under the outlet.

2. A device of the class described including a trough, supporting strips at the sides thereof, bolts connecting the strips and bearing on the sides, said bolts being adjustably engaged by the strips, a cover supported by said strips, a depending longitudinal partition on the cover and above the center of the trough, a tank having upper and lower compartments, and wings on the wall of the lower compartment for receiving the trough therebetween, one end of the trough being insertable into the lower compartment, said upper compartment having an outlet into the trough.

3. The combination with a trough, supporting strips at the sides thereof, transverse bolts bearing on the sides of the trough and adjustably engaged by the strips, a cover supported by said strips and extending longitudinally above the trough, a depending longitudinal partition on the cover and above the center of the trough, said partition having a serrated lower edge, a tank opening into the trough, and wings on the wall of the tank for receiving the trough therebetween.

In testimony that I claim the foregoing as my own, I have hereto affixed my signature in the presence of two witnesses.

ORVILLE A. THRASHER.
